Levi Moses of Janesville Wis.

DES. 2445

Letters Patent No. 2445, Dated Sept. 25, 1866

Design for a Burial Case

The schedule referred to in this Letters Patent and making part of the same.

To all whom it may concern.

Be it known that I, Levi Moses, of Janesville in the County of Rock and State of Wisconsin have invented a new and ornamental Design for a Burial Case; and I do hereby declare that the following is a full, clear and exact description thereof, which will enable others skilled in the art to understand the same, reference being had to the accompanying drawing forming part of this Specification.

The drawing is a perspective view of my improvement. My improvement relates to the cover A, of the coffin or burial case and consists in having an ornamental rebate or molding A, made on the edge of the cover from which rebate the cover rises in an ornamental oval form B, as seen in the drawing these formations producing a harmonious and beautiful Design.

Having thus described my invention I claim as new and desire to secure by Letters Patent,

The ornamental Design for the cover of a Burial Case, as shown & described. The above Specification of my invention signed by me this 21st day of July A.D. 1866
Witnessed;
